UNITED STATES PATENT OFFICE.

MAX DONAUER, OF ELYRIA, OHIO, ASSIGNOR TO THE ELYRIA ENAMELED PRODUCTS COMPANY, OF ELYRIA, OHIO, A CORPORATION OF OHIO.

LIQUID-MIXING MEANS.

Application filed July 1, 1920. Serial No. 393,430.

To all whom it may concern:

Be it known that I, MAX DONAUER, a citizen of the United States, residing at Elyria, in the county of Lorain and State 5 of Ohio, have invented certain new and useful Improvements in Liquid-Mixing Means; and I do hereby declare the following to be a full, clear, and exact description of my invention, such as will enable 10 others skilled in the art to which it appertains to make and use the same.

My invention relates to improvements for agitating the contents of such vessels as tanks, vats and the like.

15 One of the objects of my invention is to provide means which will more quickly, thoroughly, effectively and uniformly expose different particles of the liquid, or liquid conveyed particles in a tank container, to the other particles of the liquid in the tank, so that if the object of the 20 operation is to cause solution, different portions of the liquid will be brought into contact with the solid particles sought to be 25 dissolved to a maximum degree in a minimum length of time and also if the object of the operation is to promote homogeneity of the liquid contents of the tank, the different 30 portions of the liquid will become intermingled very efficiently.

It is highly desirable to realize the above and other results which may be secured in the use of my invention, by the use of apparatus which is cheap to construct, simple 35 to and convenient to operate. I aim to provide such apparatus, and it is one of the objects of my invention to provide this apparatus, in such form as will give most efficient mode of operation to achieve the 40 results sought for. These and other objects of my invention will be better understood from a description of an embodiment thereof.

Referring to the drawings, in Figure 1 45 is a sectional view taken along line 1—1 of Figure 2 looking in the direction of the arrow V.

Figure 2 is a horizontal sectional view 50 of my invention. Referring now to the drawing and to the embodiment of the drawing illustrated therein, at A is shown a tank or vat which is here shown as having a waist portion, comprising sections B and C, which are herein shown as cylindrical 55 in form. The bottom wall of the tank is

composed of an invert cone section D, the three sections, B, C and D, being assembled together at junctions E and F in any suitable manner, such as welding or by bolting the sections together or in any desired way. 60 Although the tank of my invention may be jacketed so as to maintain the walls of the tank in contact with a heating or cooling medium, for the sake of simplicity of disclosure of my invention, I do not so illustrate the embodiment herein. The tank may be supported in various ways, such as by hanging from the beams 2 and 3 to which its top flange is bolted and in which case the tank may depend from the floor of a 70 room, or it may be mounted on supporting means, such as columns, if desired. An exhaust opening for discharging the contents of the tank is shown at G to which is connected a pipe H, in which pipe valve 4 75 may be placed adapted to close the passage when desired. The bottom portion D, which in the embodiment illustrated and described, is shown as cone shaped, but which shape might be varied if desired, is perforated at J to admit a propeller shaft K on the end of which inside the tank is mounted a propeller L and on the end outside the tank is mounted a pulley M, or other power transmitting means as may be desired. 80 Such a case, rotates in a vertical plane and the space to the rear of the propeller at its periphery is therefore considerably restricted, particularly at the lower portions thereof, due to the close approach of the 90 tapering bottom to the rear edge of the rotating propeller blades when such blades are traversing the lower portion of their circular path.

The operation of the embodiment of my 95 invention illustrated will first be described, assuming that the propeller is so pitched as to be called a left handed propeller and that the propeller is rotated in such a direction as, that viewed from the middle of the tank 100 in front of the propeller, would cause it to rotate counter-clockwise.

Under such a condition, the propeller will hurl liquid peripherally of its blades, some of the liquid proceeding downwardly in the 105 direction of the arrow shown in Figure 2 at 5, and these currents will travel to the lowermost portion of the cone bottom and being deflected again in various directions will convey any sediment which would 110

otherwise be deposited in this lowermost portion, up into the higher levels of the tank, which high levels of liquid are in a continuous state of agitation caused by 5 other currents directed by the propeller.

I find that a propeller operating in a tank as has been described produces an agitation of the tank contents which is most efficient and satisfactory.

10 I also find that when the direction of the propeller is reversed that the peripherally hurled fluids traverse the bottom of the tank in very much the same manner as described before, and although the direction 15 of some of the other currents is reversed, the mode of operation previously described is maintained and efficient agitation is produced.

Having thus described my invention, I 20 wish it to be understood that the same is not limited to the aforesaid embodiment herein illustrated and described, as my invention may be embodied in other structures which still come within the spirit and 25 scope of my invention.

I claim:

1. In a device of the class described, a tank, inclined side walls and a bottom wall therefor, a propeller shaft extending substantially horizontally through the bottom wall at a point near its junction with the 30 said side walls, and a rotatable pitched propeller on the said shaft, said propeller being located closely in front of and above an adjacent portion of said bottom wall, and the said bottom wall being downwardly dished.

2. In a device of the class described, a tank, inclined side walls and a bottom wall therefor, a propeller shaft extending substantially horizontally through the bottom wall at a point near its junction with the 40 said side walls, and a rotatable pitched propeller on the said shaft, said propeller being located closely in front of and above an adjacent portion of said bottom wall, and the said bottom wall being cone-shaped.

3. In a device of the class described, a tank, inclined side walls and a bottom wall therefor, a propeller shaft extending substantially horizontally through the bottom wall at a point near its junction with the 50 said side walls, and a rotatable pitched propeller on the said shaft, said propeller being located closely in front of and above an adjacent portion of said bottom wall, said bottom wall being downwardly inclined towards its center.

4. In a device of the class described, a tank, inclined side walls and a bottom wall 60 therefor, a propeller shaft extending substantially horizontally through the bottom wall at a point near its junction with the said side walls, and a rotatable pitched propeller on the said shaft, said propeller being located in front of and above an adjacent

portion of said bottom wall, said bottom wall being downwardly inclined towards its center, and said propeller being located relatively near one side of the downwardly inclined wall.

5. In a device of the class described, a tank, inclined side walls and a bottom wall therefor, a propeller shaft extending substantially horizontally through the bottom wall at a point near its junction with the 75 said side walls, and a rotatable pitched propeller on the said shaft, said propeller being located closely in front of and above an adjacent portion of said bottom wall, and said bottom wall being cone shaped the base of the 80 cone joining the side wall bottom edges, and the apex being perforated to permit the egress of the contents of the tank.

6. In a device of the class described, a tank, inclined side walls and a bottom wall 85 therefor, a propeller shaft extending substantially horizontally through the bottom wall at a point near its junction with the said side walls, and a rotatable pitched propeller on the said shaft, said propeller being located closely in front of and above an adjacent portion of said bottom wall, said bottom wall being cone-shaped the base of the 90 cone joining the side wall bottom edges, and the apex being perforated to permit the egress of the contents of the tank, and said propeller rotating in a substantially vertical plane substantially within the tank bottom.

7. In a device of the class described, a tank, inclined side walls therefor, a propeller shaft extending substantially horizontally through the bottom wall at a point near its junction with the said side walls, and a rotatable pitched propeller on the said shaft and adapted to rotate in a substantially vertical plane disposed closely adjacent the point where the said shaft passes through the said bottom wall, and said bottom wall being cone shaped, the base of the cone joining the side wall bottom edges, and the apex 100 being perforated to permit the egress of the contents of the tank.

8. In a device of the class described, a tank, inclined side walls and a bottom wall therefor, a propeller shaft extending substantially horizontally through the bottom wall at a point near its junction with the said side walls, and a rotatable pitched propeller on the said shaft and adapted to rotate in a substantially vertical plane disposed closely adjacent the point where the 115 said shaft passes through the said bottom wall, said bottom wall being cone shaped the base of the cone joining the side wall bottom edges, and the apex being perforated to permit the egress of the contents of the tank, and said propeller rotating in a substantially vertical plane substantially within the tank bottom.

9. In a device of the class described, a 130

tank, inclined side walls and a bottom wall therefor, a propeller shaft extending substantially horizontally through the bottom wall at a point near its junction with the 5 said side walls, and a rotatable pitched propeller on the said shaft and adapted to rotate in a substantially vertical plane disposed closely adjacent the point where the

said shaft passes through the said bottom wall, and said propeller rotating in a substantially vertical plane substantially within in the tank bottom.

In witness whereof, I have hereunto signed my name this 25th day of June, 1920.

MAX DONAUER.
